(57) **CLAIM**

The ornamental design for a combined bottle and holder, as shown and described.

DESCRIPTION

FIG. 1 is a front perspective view of a combined bottle and holder showing our new design;

FIG. 2 is a left side perspective view of a combined bottle and holder thereof;

FIG. 3 is a rear perspective view of a combined bottle and holder thereof;

FIG. 4 is a top view of the combined bottle and holder thereof; and,

FIG. 5 is a bottom view of the combined bottle and holder thereof.

The broken lines in FIG. 5 depict portions of the combined bottle and holder and form no part of the claimed design.

1 Claim, 5 Drawing Sheets
